UNITED STATES PATENT OFFICE.

CLARENCE VREDENBURGH, OF LARCHMONT, NEW YORK.

DESIGN FOR A FOUNTAIN PEN.

Application filed October 8, 1927. Serial No. 23,670. Term of patent 14 years.

To all whom it may concern:

Be it known that I, CLARENCE VREDENBURGH, a citizen of the United States of America, residing at Larchmont, county of Westchester, State of New York, have invented a new, original, and ornamental Design for Fountain Pens, of which the following is a specification, reference being had to the accompanying drawing, forming a part thereof.

The figure is a perspective view of a fountain pen showing my new design.

I claim:

The ornamental design for a fountain pen substantially as shown.

CLARENCE VREDENBURGH.
